Patented Mar. 17, 1914.

UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,090,480.

Specification of Letters Patent. Patented Mar. 17, 1914.

Application filed December 16, 1910. Serial No. 597,648.

To all whom it may concern:

Be it known that I, ALFRED G. F. KUROWSKI, a citizen of the United States, residing in the borough of Brooklyn, city of New York, in the county of Kings and State of New York, have invented certain new and useful Improvements in Type-Writing Machines, of which the following is a specification.

This invention relates to means for indicating to the operator of a typewriting machine when the page of writing is finished, so that he may not attempt to write too close to the bottom edge of the work sheet. It has been found difficult to construct practicable devices of this nature, principally for the reason that space is very limited in the vicinity of the printing point on the typewriter, and it has been found particularly difficult to arrange within this limited space a practicable indicator which can be controlled by the work sheet.

One of the objects of this invention is to overcome this difficulty; and I arrange the mechanism where it is not only removed from the printing line, but is also accessible, and is readily controlled by the work sheet.

One of the main distinctions between the present and prior constructions, lies in a change in the method of operation. Instead of having the platen locked (or other indication given) as soon as the sheet operates the locking or indicating mechanism, I contrive to postpone the locking or indicating until the work sheet has advanced for a substantial distance after operating the locking or indicating mechanism. Heretofore such mechanism has been operated at the writing of the last line on the sheet. According to my invention, the indicating mechanism may be operated when there are still many lines to be written upon the sheet. Although the indicating mechanism is set, still the actual giving of the indication can be deferred until the remaining lines are written upon the sheet; whereupon the lock or other indicator will become effective at the writing of the final line on the page. I provide an interponent between the sheet-operated dog or other indicating device, and a driver or part upon the rotating platen; effective operation of the indicator or lock being deferred until said driver or part upon the rotating platen engages said interponent; whereupon the operator is notified that the end of the page has

been reached, preferably by means of causing the platen to be locked against further rotation. He has been notified aurally previously by the click of the dog 19 as it engages the ratchet, optically by the flicker of the finger-piece 24 at the same moment, and digitally by the sensation of increased resistance to the movement of the feeding lever 6, that the end of the line is near. Between the platen and the interponent there is preferably a provision for adjustment, and this adjustment may be made to cover an ample range, so that either a narrow or deep margin may be left at the bottom of the page.

In the accompanying drawings, Figure 1 is a perspective view illustrating one embodiment of the invention applied to the platen frame of an Underwood writing machine. Fig. 2 is an end view, showing the dog held released by a work sheet. Fig. 3 shows the positions assumed by the parts at the moment the dog is tripped. Fig. 4 shows the platen arrested against rotation. Fig. 5 shows the dog released and the parts reset. Figs. 6, 7 and 8 are perspective detail views of the stop or driver and its mount, the interponent and the adjustable member respectively. Fig. 9 is a sectional view taken through the stop mechanism, the adjustable member being released.

A platen 1 is fixed on an axle 2 journaled in ends 3 of a platen frame. The usual paper shelf 5 connects the ends 3. Pressure against a lever 6 operates through a slide 7 and pawl 8 to turn a line-space wheel 9 on the axle 2 and rotate the platen. The platen may also be turned by the finger wheels 10. Pressure rolls 11, 11^a, running on the bottom of the platen 1, advance the work sheets as the platen is turned.

To indicate when the sheet 4 has been sufficiently filled, and to prevent the writing of additional lines, the rotation of the platen is arrested by a stop or driver 12 (located eccentrically of a disk or mount 13 having a hub 17 fast on the axle 2), which stop may strike an interponent 16. Said interponent in the present instance is formed by a barrel 16 having a semi-circular slot 15 against one end of which the stop strikes to arrest the platen. Said interponent is journaled on the hub 17 of the disk 13, and preferably fits over the disk 13, (Fig. 9) which steadies the interponent. Axial displacement of said interponent away from

the disk is prevented by a shoulder 18 on the stop or driver 12, which overhangs the edges of the slot 15. A spring 22 (Fig. 6) preferably housed between the disk 13 and the interponent 16 holds the interponent in initial position, the rear end 23 of the slot 15 being pressed against the stop 12 as the latter rotates (Figs. 2 and 3) to cause the interponent normally to turn with the platen. The interponent may be arrested by a sheet-controlled dog 19. Said dog is fast on a shaft 20 journaled in the ends 3 of the platen frame and is rocked by a spring 25 to engage a circular rack or ratchet 21 on the interponent 16. The spring 25 normally causes a trip 26 to enter a slot 27 in the paper shelf 5, to enable the dog 19 to engage the rack 21; but the work-sheet 4, when in position against the platen, passes beneath and supports the trip out of said notch to hold the dog idle. The trip 26 depends into the paper throat from the shaft 20 at a point about midway of the length of said throat, to engage the sheet at a point about equidistant from its side edges so that the pressure of the trip will not act as a brake to retard and skew the sheet as it is fed in line-spacing direction. The interponent 16 turns with the platen 1 as the sheet is advanced, due to the tension of the spring 22 which presses the rear end 23 of the slot 15 against the stop 12. As the bottom edge of the sheet clears the trip 26, (Fig. 3) the spring 25 becomes effective to rock the trip to its slot 27, such movement also rocking the shaft 20 to cause the dog 19 to engage the rack 21 to arrest the interponent 16. Further turning of the platen in line-space direction brings the stop 12 against the forward end 14 of the slot 15 (Fig. 4), to lock the platen against rotation, (and incidentally tensions the spring 22). Upon releasing the dog 19, the spring 22 resets the interponent 16 by rotating the latter on the hub 17 until the rear end 23 of the slot 15 strikes the stop 12 (Fig. 5). The stop 12, in the instance given, travels from end to end of the slot 15 and as the tripping of the dog 19 always occurs when the bottom edge of the sheet is at a constant distance from the printing line, a uniform depth of bottom margin on the successive sheets is maintained. If it is desired to make a correction in a previously written line, after the bottom edge of the sheet has passed the trip 26, and before the sheet is removed from the machine, the platen 1 is reversed by turning the finger wheel 10. This rotates the disk 13 and stop 12 until the latter brings up against the rear end 23 of slot 15, to cause the interponent 16 and rack 21 to turn with the platen. Such reverse rotation of the rack cams the dog 19 out of mesh with the rack to lift the trip 26 out of its slot 27 at the moment when the bottom edge

of the sheet engages the trip, to enable said edge to slip freely beneath the trip and hold the dog idle. The trip 26 terminates in an upwardly and forwardly curved guide 28 which rises sufficiently above the paper shelf to catch the bottom edges when the platen is rotated backwardly, and cams said sheets downwardly to prevent fanning out, and to direct such bottom edges toward the paper shelf. Depression of a finger piece 24 may rock the shaft 20 to release the dog 19 if desired, to permit the platen to be turned, said finger-piece lying in position to be engaged in the operation of inserting the sheet 4.

The distance traversed by the stop 12 subsequently to the locking of the interponent 16, determines the depth of margin left at the bottom of the sheet. This distance may be varied by the adjustment of a member 29 relatively to the stop 12. Such member, in the present instance, is formed by an arm extending across the slot 15 and having a hub 31 journaled on the hub 17. Said arm is held against rotation relatively to the interponent 16 by a detent 33 preferably entering between any two teeth of the circular rack 21. To regulate the depth of the margin, the arm 29 is first slid axially (Fig. 9) to release the detent 33 from the rack 21 after which it is rotated on the hub 17 toward or from the stop 12 to decrease or increase the distance between said stop and the arm. When properly adjusted the arm is returned toward the interponent 16 to enter the detent 33 between the teeth of the rack, said rack preferably having teeth equal in number to the teeth of the line space wheel 9, so that the platen will be arrested at the end of a line space. A spring 34 prevents accidental disengagement of the detent and rack. The hub 31 is of such length as to hold the arm parallel with the interponent 16 and may serve as a stop to limit the releasing movement of the arm, (Fig. 9). The regulating arm 29 turns with the interponent 16 as the sheet is advanced, and is arrested therewith by the dog 19. The bottom margin is narrowest when the stop 12 travels the full length of slot 15 after the arrest of the interponent 16. Therefore, by setting the arm 29 between the stop 12 (when in normal position, Fig. 2) and the end 14 of the slot 15, the travel of the stop after the arrest of the interponent, is reduced, and consequently the travel of the platen is shortened, to increase the depth of the margin.

To ascertain the necessary adjustment of the regulating member or arm 29 relatively to the stop 12 for any desired depth of margin, the arm is first adjusted to idle position behind the end 14 of the slot 15, after which a sheet is introduced into the machine, and the platen turned until the desired length of sheet has passed the print-

ing line, whereupon the platen is held idle and the arm is adjusted to engage the stop, which operation, in effect, shortens the slot.

To afford support when an attempt is made to operate the locked platen by the line-spacing mechanism, the interponent preferably has a pair of diametrically opposed semi-circular slots 15, 15^a through which project similarly opposed stops or drivers 12, 12^a, two oppositely extending regulating arms 29, 29^a being carried by the hub 31, to cooperate with the stops. For convenience of adjustment, said arms 29, 29^a may be connected by a knurled annulus 15 35 which is readily grasped when an adjustment is to be made.

Variations may be resorted to within the scope of the invention, and portions of the improvements may be used without others.

2. Having thus described my invention, I claim:

1. In a typewriting machine, the combination with a rotatable platen, of a driver fast on the axle of said platen, an interponent to be engaged by the driver to indicate some conditions, said interponent normally turning with the platen, a sheet-controlled dog to arrest the interponent, and means to reset the interponent upon release of the dog.

2. In a typewriting machine, the combination with a rotatable platen, of a driver fast on the axle of said platen, an interponent spaced apart from the driver to provide lost motion, said interponent normally turning with the platen, a sheet-controlled dog to arrest the interponent in the path of the driver to indicate something to the operator, and means to reset the interponent upon release of the dog.

3. In a typewriting machine, the combination with a rotatable platen, of a driver turning therewith, an interponent normally spaced apart from the driver and turning with the platen, a sheet-controlled trip moving a dog to arrest the interponent in the path of the driver to indicate something, and means to reset the interponent upon the release of the dog.

4. In a typewriting machine, the combination with a rotatable platen of a driver turning therewith, an interponent normally spaced apart from the driver and turning with the platen, a sheet-controlled trip moving a dog to arrest the interponent in the path of the driver to indicate something, and means tensioned by the rotation of the platen after the arrest of the interponent, to reset the interponent upon the release of the dog.

5. In a typewriting machine, the combination with a rotatable platen, of paper-end indicating mechanism including a sheet-controlled dog, a rotatable interponent turning on an axis concentric with the platen and rested by said dog, a driver fast on the

platen axle to engage said interponent when arrested, to indicate something, and means to yieldingly hold the interponent in advance of the driver until arrested by the dog, and to reset the interponent after the release of the dog.

6. In a typewriting machine, the combination with a rotatable platen, of means to arrest the platen including a dog, a toothed interponent connected to the platen and engaged by the dog, and a pivoted sheet-controlled strip to maintain the dog idle, normally in idle position, terminating in a guide to direct the bottom edge of the sheet toward the paper shelf when the feed is reversed subsequently to the passage of said bottom edge from beneath the trip.

7. In a typewriting machine, the combination with a rotatable platen, of means to arrest the platen including a dog, a toothed interponent connected to the platen and engaged by the dog, and a pivoted sheet-controlled strip to maintain the dog idle, normally supported by the sheet and being vibrated when the sheet feed is reversed to avoid obstructing the return of the bottom edge of the sheet.

8. In a typewriting machine, the combination with a rotatable platen arranged to feed sheets, of means to arrest the platen when turned in one direction, including a trip normally lying in the path of the sheets, said arresting means comprising a member automatically effective to move the trip to permit sheets to pass it when the direction of rotation of the platen is reversed.

9. In a typewriting machine, the combination with a rotatable platen, of a driver turning therewith, means for arresting the driver, said means comprising a regulating member adjustable in the path of the driver and rotatable with the platen to provide lost motion for the arresting means, and sheet-controlled means to arrest the adjustable member.

10. In a typewriting machine, the combination with a rotatable platen, of a driver fixed to turn therewith, an interponent loosely mounted relatively to the platen and in the path of the driver, a regulating member borne by the interponent, and sheet-controlled means to arrest the interponent and regulating member.

11. In a typewriting machine, the combination with a rotatable platen, of a driver fixed to turn therewith, an interponent loosely mounted relatively to the platen and in the path of the driver, a regulating member borne by the interponent and adjustable relatively thereto, means to hold the member where adjusted on the interponent, and sheet-controlled means to arrest the interponent and regulating member.

12. In a typewriting machine, the combination with a rotatable platen and its axle,

of a driver fixed to turn therewith, an interponent loose on the axle, and held a predetermined distance in advance of the driver as the latter rotates to provide lost motion, and sheet-controlled means to arrest the interponent.

13. In a typewriting machine, the combination with a rotatable platen, of a driver fixed to turn with the platen about its axis, 10 an interponent loosely mounted relatively to the platen and turning with the platen, said interponent having a series of notches, a regulating member adjustable relatively to the interponent and having a detent to enter 15 any of the notches to hold the interponent and regulating member where adjusted, relatively to each other, the driver located between the interponent and regulating member, and a sheet-controlled dog to enter any 20 of said notches to arrest the interponent, and its member relatively to the driver.

14. In a typewriting machine, the combination with a rotatable platen of a driver fixed to turn with the platen about its axis, 25 an interponent loosely mounted relatively to the platen and having a regulating member connected thereto, one in advance and the other in rear of the driver, yielding means to hold the interponent against the 30 back of the driver, and sheet-controlled means to arrest the interponent.

15. In a typewriting machine, the combination with a rotatable platen having an axle, of a driver fixed to turn with the 35 platen, an interponent rotatable on the axle and having a series of notches, a regulating member having a detent to enter any of the notches to connect it to the interponent against independent rotation, means to press 40 the interponent against the back of the driver whereby the regulating member is held a predetermined distance in advance of the driver as the latter turns, and a sheet-controlled dog to enter any of the notches 45 on the interponent to arrest the rotation thereof and of the regulating member.

16. In a typewriting machine, the combination with a rotatable platen having an axle, of a driver fixed to turn with the 50 platen, an interponent rotatable on the axle and having a series of notches, a regulating member having a detent to enter any of the notches to connect it to the interponent against independent rotation, said regulating 55 member being axially shiftable relatively to the interponent, a spring to prevent accidental disengagement of the regulating member, means to cause the interponent normally to turn with the platen, and a sheet-controlled dog to arrest the interponent. 60

17. In a typewriting machine, the combination with a rotatable platen having an axle, of a driver fixed to turn with the axle, a regu-

lating member borne by the interponent, a releasable connection between the member and interponent to effect relative adjustment thereof, yielding means to cause said interponent to follow the driver to hold the regulating member a predetermined distance in advance of the driver as the latter turns, and a sheet-controlled dog to arrest the interponent.

18. In a typewriting machine, the combination with a rotatable platen of a driver fixed to turn therewith, a sheet-controlled dog, a ratchet rotatable independently of the platen and arrested by the dog, a regulating member adjustably connected to the ratchet and lying in the path of the driver, yielding means to cause the ratchet to turn with the platen until arrested by the dog and to reset the regulating member upon the release of the ratchet.

19. In a typewriting machine, the combination with a rotatable platen, of a driver fixed to turn therewith, an interponent normally turning with the platen in the path of the driver, a trip mechanism to hold the interponent against turning, and means to reset the interponent relatively to the driver upon the release of the trip mechanism.

20. In a typewriting machine, the combination with a rotatable platen having an axle, of a driver fixed to turn with the 95 platen, an interponent loosely mounted relatively to the platen and having an arcuate slot through which the driver projects, yielding means to press one end of the slot against the driver to cause the interponent to turn 100 with the platen, a regulating arm journaled relatively to the axle, and extending across the slot, said arm adjustably connected to the interponent to turn therewith, and sheet-controlled means engaging the interponent 105 to arrest the arm.

21. In a typewriting machine, the combination with a platen, of a driver fixed to turn therewith, an interponent loosely mounted relatively to the platen, and having a slot in which the driver is entered, yielding means to hold the interponent in set position as the platen turns, a sheet-controlled dog to arrest the interponent, and a regulating member adjustably secured to the interponent in the path of the driver to control the depth of margin at the bottom edge of a sheet.

22. In a typewriting machine, the combination with a platen, of a driver fixed to turn therewith, an interponent loosely mounted relatively to the platen, and having a slot in which the driver is entered, yielding means to hold the interponent in set position as the platen turns, a sheet-controlled dog to arrest the interponent, an axially shiftable regulating member adjustable relatively to and lying in the path of

- the driver, and means to secure the shift-
able member to the interponent where ad-
justed.
23. In a typewriting machine, the combi-
nation with a rotatable platen arranged to
feed a sheet, of a sheet controlled indicator
device tripped by said sheet to become ef-
fective at the writing of a predetermined
line when the sheet has advanced a substan-
tial distance after tripping the device, an
interponent between the platen and indicator
device, and means for automatically re-
storing said interponent at the insertion of
a new sheet.
- 15 24. In a typewriting machine, the combi-
nation with a rotatable platen, of a driver
turning with the platen, a sheet controlled
dog, an interponent providing loose motion
between the dog and the driver engaged by
20 the dog when tripped to permit some in-
dication to be given later in the operation
of the device, and means for automatically
restoring said interponent, substantially as
described.
- 25 25. In a typewriting machine, the combi-
nation with a rotatable platen, of a paper-
end indicator comprising a driver fixed to
turn with the platen and projecting through
a slot formed in an interponent, one end of
30 which slot is held against the driver by a
spring to cause the interponent to turn nor-
mally with the driver, the sheet adapted to
support a trip which holds a dog in idle po-
sition until the bottom edge of the sheet
35 passes the trip whereupon a spring causes
the dog to arrest the interponent, the driver
traveling in the slot as the platen is fur-
ther rotated until it strikes the opposite end
of the slot or a regulating member releas-
40 ably connected to the interponent.
26. The combination with a rotatable
platen and coöperating elements arranged to
feed a sheet, of a line spacing mechanism, a
driver turning therewith, an indicator con-
45 trolled by the passage of a sheet, connections,
including a lost motion feature, between the
indicator and the driver, and means for ad-
justing the parts to determine extent of lost
motion.
- 50 27. The combination with a rotatable
platen and coöperating means arranged to
feed a sheet, said platen having a stop se-
cured thereto of an arresting device coöp-
erating with the stop and arranged so as to
55 be in indicating relation to the final edge of
a sheet, means having a lost motion feature
therein between said arresting device and
stop, and an element adjustable about the
axis of the platen and mechanically related
60 to the platen and the arresting device, so as
to define at will, the extent of the lost motion.
28. The combination with a rotatable
platen arranged to feed a sheet, of a stop
- fast to the platen, a toothed wheel concentric 65
with the platen, an indicating means oper-
ated by the passage of a sheet to engage said
toothed wheel, a lost motion member be-
tween said toothed wheel and said stop, and
a pin swinging around the axle of said 70
platen to engage a selected tooth on the wheel
to adjust the amount of said lost motion.
29. In a typewriter, a lost motion mecha-
nism comprising an axle, a driver fast on
the axle, a stop on the driver, a disk loose on 75
the axle having an arcuate slot in which
said stop rides, a second disk loose on said
axle having an arcuate slot also embracing
said stop, and means for locking said disks
together, to vary the length of open slot in 80
which said stop can ride.
30. In a typewriting machine, the combi-
nation with a rotatable platen, of a driver
turning therewith, an interponent providing
lost motion members arranged to permit 85
said platen to turn freely and then arrest it
by said driver, said interponent turning with
the platen and normally held to provide said
lost motion, and sheet-controlled trip mecha-
nism operated when the bottom edge of the 90
sheet is remote from the printing line, to
arrest the interponent.
31. The combination with a rotatable
platen, of an indicator operated by rotation
of the platen, a toothed wheel fast on the 95
platen, and a disk rotatable on the platen
comprising a detent settable between the
teeth of said toothed wheel to adjust the
operation of said indicator.
32. The combination with a rotatable 100
platen, of an indicator operated by rotation
of the platen, a toothed wheel fast on the
platen, a disk rotatable on the axle of said
platen, a detent fast on said disk, and a
spring urging said disk against said toothed 105
wheel to cause said detent to engage said
toothed wheel and adjust the operation of
said indicator.
33. The combination with a line-feeding
platen, of a settable device whose movement 110
depends upon the passage thereby of the
bottom margin of the work-sheet, some
member of said device being in engagement
with said work sheet, a member moving with
the platen but arrested by said sheet-con- 115
trolled device when the latter is set, means
to enable the advancing platen to coöperate
with said arrested member for subsequently
warning the operator of the approach of
said bottom edge to the printing line on the 120
platen, and an axially movable rotatable
member mounted concentrically with said
first named member for determining the ex-
tent of the line-spacing interval between the
setting of said settable device, and the giv- 125
ing of the warning to the operator.
34. The combination of a revolute platen,
a member movable around the platen axis

relatively to the platen, a second member
axially and rotatably adjustable on the hub
of the first member, means controlled by the
work-sheet for arresting the first member,
and means to enable the platen to coöperate
with the second member, when the same is
so arrested, for warning the operator of the

approach of the bottom edge of the work-
sheet to the printing point on the machine.
